(74) Attorney, Agent, or Firm — George R. McGuire;
Bond Schoeneck & King PLLC(57) **CLAIM**The ornamental design for an odor aerosol can, as shown
and described.

DESCRIPTION

FIG. 1 is a perspective view of a new and ornamental design
for an odor aerosol can;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan elevation view thereof; and,

FIG. 7 is a bottom plan elevation view thereof.

The broken lines show portions for an odor aerosol can that
form no part of the claimed design.**1 Claim, 6 Drawing Sheets**FIG. 1
